UNITED STATES PATENT OFFICE.

WILLIAM AUGUSTUS COOK, OF BROOKLYN, NEW YORK.

REED-ORGAN.

1,383,289.

Specification of Letters Patent.

Patented July 5, 1921.

Application filed January 17, 1920. Serial No. 352,178.

To all whom it may concern:

Be it known that I, WILLIAM AUGUSTUS COOK, a citizen of the United States, residing at Brooklyn, in the county of Kings, 5 State of New York, have invented certain new and useful Improvements in Reed-Organs; and I do hereby declare the following to be a full, clear, and exact description of the invention, such as will enable others 10 skilled in the art to which it appertains to make and use the same.

This invention relates to reed organs and is particularly applicable to pneumatically operated self-playing organs controlled by a 15 perforated note sheet.

Reed organs have been heretofore relatively unsatisfactory as musical instruments, largely because of the thinness of the tones and lack of volume. In other words, such 20 organs have depended upon a single reed for each tone with the result that the music produced has not been pleasing to the average ear. This is particularly true of reed organs of the self-playing class and they have, 25 therefore, met with very limited demand in the trade.

The object of the present invention is to provide an organ capable of producing a large volume of tone which is of a pleasing 30 character, because of the blending of sound produced by a plurality of reeds, tuned to vibrate in unison.

A further object of the invention is the provision of an organ embodying a novel arrangement of the reeds and provided with an amplifier and means for readily controlling the volume of tone.

Further objects and advantages reside in various combinations, as will be apparent by 40 reference to the following specification and the accompanying drawing in which I have illustrated the preferred embodiment of my invention.

In the drawings, 45 Figure 1 is a transverse section through the organ;

Fig. 2 is a vertical longitudinal section through the organ illustrating the banks of reed boxes;

Fig. 3 is an enlarged detail of a reed box and the controlling means therefor; and

Fig. 4 is a detail in section of the reed boxes for the larger reeds pertaining to the base octave of the organ.

55 Referring to the drawing, 5 indicates a suitable case which may be varied in form,

being adapted to house the mechanism and having a key-board support 6 projecting from the front thereof to protect the keys 7 which are of usual form and are supported 60 on pivots 8. Above the key-board support, the case is recessed to receive rolls 9 on which the note sheet is wound. The driving mechanism for the rolls may be of any suitable character well known in the art and is 65 consequently not illustrated in the drawing, it being understood that the note sheet 10 passes from one roll to the other over a tracker-board 11, having the usual passages 12 therein which are connected by tubes 13 70 to the valve cases 14. The valves within the cases 14 control the operating pneumatics 15 and may be of any usual form and construction. As is usual in player mechanisms, when the perforation in the note sheet passes 75 the corresponding passage 12 in the tracker-board, air is permitted to enter through the corresponding valve in the valve case 14 and the actuating pneumatic is thus connected to the exhaust and is collapsed, while the 80 perforation continues to pass the tracker-board.

The necessary suction is maintained by a bellows 16 disposed in the lower part of the case 5 and connected to a pair of treadles 85 17 by flexible cables 18 which pass over pulleys 19 and are secured to the front board of the bellows. Obviously other forms of connection may be employed. A spring 20 tends to collapse the bellows and when the 90 spring is flexed through the actuation of the treadles 17, the bellows withdraws air from an equalizer 21 which is normally expanded by a spring 22. The air withdrawn passes through outlets 23 controlled by flap valves 95 24 and as the bellows is collapsed by the spring 20, the air escapes through outlets 25 controlled by flap valves 26. As the back board of the equalizer is hinged at 27, the vacuum maintained therein is controlled by 100 the spring 22 and when the suction is increased the back board swings forwardly thus reducing the capacity of the equalizer. If the treadles are actuated more slowly, the spring 22 expands the equalizer, increasing 105 its volume capacity and thus tending to maintain a constant suction. Behind the operating pneumatics 15, I provide a plurality of reeds, each arranged in a suitable box and disposed one above 110 the other to form a bank, it being understood that all of the reeds in each bank are

tuned to vibrate in unison. Thus a single bank is provided for each note which the organ is intended to produce. The boxes 28 are each provided with a diaphragm or 5 reed support 29, having an opening 30 in which the reed 31 is adapted to vibrate. Above the reed is a partition 32, having an opening 33 therein which is controlled by a pallet 34 hinged at 35 to the partition. 10 Each of the pallets 34 in a single bank, is connected to an operating rod 36 which passes downwardly and rests upon a lever 37, a spring 38 being disposed between the lowest box and a collar 39 on the rod 36 15 to normally hold the covers 34 in closed position. Each lever 37 is pivotally supported in a bracket 40 and is connected by a stem 41 to one of the operating pneumatics 15. Thus, when an operating pneumatic is col- 20 lapsed, the corresponding rod 36 is actuated and each of the pallets 34 which are connected thereto, are lifted. Obviously when the organ is in operation, a number of the rods 36 may be actuated simultaneously in 25 accordance with the perforations on the note sheet and the corresponding pallets 34 are opened and closed as the music progresses.

The reed boxes are closed above the pallets 34 to provide air chambers which are 30 normally closed by hinged swells 42 preferably provided with dampers 43 of felt or other suitable material. Each of the swells 42 has a plurality of perforations 44 corresponding to the respective air chambers and air is admitted through the perforations and 35 passes, when the pallets 34 are opened, through the reed boxes and into vertical conduits 45 communicating with the reed boxes, beneath the reeds, and with a wind 40 chest 46, which, in turn communicates with the equalizer 21. Obviously the production of a given tone depends upon the passage of air across the corresponding reeds in the reed 45 boxes and air is permitted to pass only when the actuating pneumatic has lifted the pallets 34. When the pallets are lifted all of the reeds of a single bank vibrate in unison and 50 are simultaneously actuated to produce a blended tone of large volume.

To permit control of the volume of tone for loud and soft effects, the hinged swells 42 are each provided with an arm 47 which is, in turn, connected to a link 48. The 55 link is secured to one arm of a bell crank lever 49 pivoted within the case, the other arm, being connected to a rod 50 extending to the front of the organ and having an operating knob or handle 51 secured to its end. 60 The rod may be actuated by a pneumatic. Thus the operator is able to control the positions of the swells 42 and vary the volume of tone.

The heavy reeds constituting the lower 65 octave are housed in separate reed boxes

52 which are arranged across the rear of the casing 5. Each reed box provides a support 53 for a reed 54 behind the opening 55 through which the air passes from an air chamber 56 to a passage 57 and thence to 70 the wind chest 46. Air is admitted to the air chamber through an opening 58 which is controlled by a pallet 59 hinged at 60 and actuated by a rod 61 and lever 62 pivoted on a bracket 63. The levers 62 are controlled 75 by corresponding actuating pneumatics 15. A spring 64 surrounds each of the rods 61, being disposed between an abutment on the reed box and a collar 65. The springs 64 hold the pallets closed except when the latter are raised by the actuating pneumatics 15. An opening 66 above each of the reed boxes 52 is normally closed by a swell 67 preferably provided with a damper 68 of felt, or other suitable material, and having 80 an opening 69 therein through which air may pass. To permit control of the volume of tone, the swell 67 is connected by a rod 70 to one arm of a bell crank 71, the other arm of which is connected to a rod 72 extending to the front of the organ and being provided with a knob or operating handle 73. Thus the operator is enabled to lift the swell 67 and increase or diminish the volume of 85 tone emitted.

Above the reed boxes and within the casing 5, I provide an amplifier 74 preferably of the form illustrated in the drawing and having a reduced neck 75 and a bell shaped mouth 76, the latter being controlled by a 90 shutter 77 which may be actuated in any suitable manner. A sheet of thin fabric 78 which permits the escape of sound waves and the entrance of air is preferably stretched across the rear of the case 5 in front of the amplifier 74 and prevents the entrance of dust to the mechanism. The direction of sound and of the air entering the reed boxes is illustrated in the drawing by the solid and dotted arrows respectively. 110

It is sometimes desirable to actuate the organ manually and accordingly the keys 7 are each engaged with levers 79 pivoted on brackets 80 and having ends 81 which rest on the levers 37 and 62. By depressing 115 the keys 7, the levers 37 and 62 may be actuated at will and independently of the pneumatics 15 which are connected to the levers 37 and 62 so as to perform their function without interfering with movement of the 120 levers when actuated by the keys 7.

From the foregoing description, it will be apparent that I have perfected an organ embodying many novel features and particularly an arrangement of reeds to vibrate in 125 unison and produce a blended tone of considerable volume. As compared with reed organs of the common and well known types, my improved organ is adapted to produce a much more pleasing tone and the volume 130

is sufficient to permit its use successfully in relatively large rooms. The volume may, however, be controlled so that the organ is adapted for smaller rooms by simple manipulation of the dampers as described. The tone produced by the reeds vibrating in unison is not to be compared with that produced by a single reed since the metallic quality of the reed tone is materially reduced or practically eliminated.

Various changes may obviously be made in the form, arrangement and construction of the parts without departing from the invention or sacrificing any of its advantages.

15 I claim:

1. In a reed organ, the combination of a plurality of vertical banks of reeds, means for inducing the passage of air through the reeds, means for controlling the passage of air through the individual banks of reeds, a plurality of swells each controlling the volume of tone from a plurality of reeds, and means for manually and simultaneously adjustably actuating the swells.

25 2. In a reed organ, the combination of a plurality of vertical banks of reeds, means for inducing the passage of air through the reeds, means for controlling the passage of air through the individual banks of reeds, a plurality of swells each controlling the volume of tone from a plurality of reeds, means for manually and simultaneously adjustably actuating the swells, an amplifier through which the sound is directed from the organ, and a damper in the throat of the amplifier.

35 3. In a reed organ, the combination of a casing providing a reed compartment, a plu-

rality of vertical banks of reeds within the compartment, means for inducing the passage of air through the reeds, means for controlling the passage of air through the individual banks of reeds, a plurality of swells each controlling the volume of tone from a plurality of reeds, means for manually and simultaneously adjustably actuating the swells, an amplifier with a reduced neck communicating with the reed compartment, and a bell mouth through which the sound is directed from the organ.

4. In a reed organ, the combination of a plurality of vertical banks of reeds, means for inducing the passage of air through the reeds, means for controlling the passage of air through the individual banks of reeds, a plurality of swells each extending over openings through which the sound issues from a plurality of reeds, and means for manually and simultaneously adjustably actuating the swells.

5. In a reed organ, the combination of a plurality of vertical banks of reeds, means for inducing the passage of air through the reeds, means for controlling the passage of air through the individual banks of reeds, a plurality of swells each extending over openings through which the sound issues from a plurality of reeds, and means for manually and simultaneously adjustably actuating the swells, including connecting means between the swells and a rod extending to the front of the organ whereby the swells are actuated.

In testimony whereof I affix my signature.

WILLIAM AUGUSTUS COOK.
